FUEL INJECTION DEVICE

Ferdinando Carlo Reggio, Detroit, Mich.

Application August 17, 1940, Serial No. 353,002

16 Claims. (Cl. 123—139)

This invention relates to a fuel supply system for internal combustion engines, and in particular to a fuel injection system for delivering liquid fuel under pressure and in measured quantities into the cylinders or into the induction manifold of the engine. More specifically the invention relates to an injector system including a governor having a hydraulic operating connection with the fuel metering pumps. In so far as the subject matter is common this invention is a continuation in part of my applications Ser. No. 236,249 filed October 21, 1938, Ser. No. 254,355 filed February 3, 1939, Ser. No. 333,529 filed May 6, 1940, and Ser. No. 346,479 filed July 20, 1940.

An object of the invention is to provide an improved arrangement of fuel system including a fuel injector, a governor, and hydraulic means for connecting the governor with the injector. Another object is to provide an injector which may be readily removed from the engine and replaced thereon. Still another object is to provide an injector which may be quickly and easily connected with and disconnected from one or more fuel lines or conduits. A still further object is to provide common means for clamping the injector on the engine, and simultaneously effecting the connection of one or more pipes or conduits therewith. Still another object is to provide an engine fuel injector, or injection pump unit, which may be hydraulically controlled, or vented or liquid cooled, so arranged that it may be quickly and easily mounted on the engine, and connected with one or more pipes or conduit containing liquid fuel or other appropriate fluid such for example as lubricating oil, or other suitable liquid coolant. Another object is to provide a simple and compact governor which is relatively inexpensive to manufacture and accurate in operation. A still further object is to provide improved safety devices for stopping the fuel supply of the engine under predetermined operating conditions.

The above and other objects of the invention will be apparent as the description proceeds; and while I have illustrated and described the preferred embodiments of the invention as they now appear to me, it will be understood that such changes may be made as fall within the scope of the appended claims. In the following description and in the claims various details will be identified by specific names for convenience but they are intended to be as generic in the application as the art will permit.

The drawings show various embodiments of my invention: Figure 1 is a transverse section show-

ing the injector of my invention and the governor for controlling the delivery of the injector. Figure 2 is a transverse elevational view of the injector of Figure 1 showing a detail of the fuel connections thereof. Figure 3 is in part a front view of the injector of Figures 1 and 2 and in part a section taken along the line 3—3 of Figure 1. Figure 4 is a partial modification of the governor shown in Figure 1. Figure 5 shows part 10 in view and part in section safety devices for stopping the engine fuel supply. Figures 6 and 7 show a modified form of injector.

Referring to Figures 1 to 3 of the drawings, the injector forming part of the invention is 15 shown as an injector of the type including in a single interchangeable unit a metering pump and a fuel discharge nozzle having their axis substantially at right angles. The injector includes a body or housing 6 in which is removably mounted a pump barrel 8 provided with a fuel inlet port 10.

A pump plunger 12 is mounted in barrel 8 and is adapted to be reciprocated from an engine-driven cam 14 by a tappet mechanism 16. The 20 plunger may be of any suitable construction, preferably of the type in which the quantity of fuel injected by the pump is controlled by an angular adjustment, or rotation of the plunger about its axis. Such type of construction is well-known 25 and therefore it is regarded unnecessary to show and describe it in greater detail. Plunger 12 is slidably but non-rotatably mounted in pinion 18 which pinion is mounted with suitable axial and radial clearance in housing 6 and engages a rack 30 reciprocable in a bore of housing 6, so that 35 an axial movement of the rack causes rotation of plunger 12 and in turn a variation of the delivery of the injector. A spacer 22 having a central fuel passage is clamped on the inner end of 40 barrel 8. The housing 6 of the injector is provided with a passage 24 formed preferably at right angles with the axis of plunger 12 and in 45 which is mounted a fuel conduit member 26 held in proper angular position by means of a dowel and slot connection 28. The outer end of conduit member 26 is seated against the end of the wall of passage 24, while the inner end thereof is provided with a head 30 adapted to be clamped against spacer 22. A check or non-return valve, 50 not shown in the drawings, is inserted in a suitable cavity between head 30 and spacer 22. The central or intermediate portion of conduit member 26 is formed with a reduced section so as to be resilient and adapted to yield within designed 55 limits.

Against the outer end of conduit member 26 there is mounted a nozzle tip member 32 clamped by means of a cap 34 screwed onto the wall of passage 24. A spring-loaded non-return fuel valve, also not shown in the drawings, is provided between the fuel conduit member 26 and the nozzle tip member 32; and a duct axially formed in the latter leads fuel to the discharge orifice 36 drilled at the end of nozzle tip member 32. The head 30 at the inner end of the fuel conduit member 26 and the spacer 22 are clamped against the barrel 8 by means of a spacer 38 which in turn is clamped by a screw plug 40. An annular seal 42 interposed between spacer 38 and screw plug 40 prevents leakage of fuel therewith. Thus all the parts of the injector may be very easily assembled or taken apart. In assembling, rack 20 is mounted in its bore; pinion 18, plunger 12, barrel 8, and spacer 22 may be introduced from the top of housing 6; then the conduit member 26 is mounted endwise through passage 24 and clamped therein by means of nozzle tip member 32 and cap 34, then the head 30 is clamped against spacer 22 by means of upper spacer 38 and screw plug 40. Since the intermediate portion of conduit member 26 has a comparatively reduced cross section, this portion will yield as it may be necessary to insure a uniformly distributed contact pressure between said head 30 and spacer 22 when screw plug 40 is tightened, thereby eliminating the danger of fuel leakage therebetween and distortion of the pump barrel 8.

The plunger 12 is formed with a head 44 and a groove 46 adjacent the outer end thereof adapted to provide a head and T-slot detachable connection with the upper portion 47 of tappet mechanism 16. Fuel enters the injector through an inlet 48 communicating by means of a duct 49 having its outer end closed by a plug 50 with the groove 51 axially machined in the barrel 8 and in the lower spacer 22, which groove establishes a fuel communication between the barrel port 10 and the passage 24. Excess fuel flows into passage 24 and leaves the injector through a duct 52 and an outlet 53. This flow of fuel, determined by a fuel transfer pump, vents the injector of all bubbles of air, vapor, or gas that may separate from the fuel and which might otherwise reach the pressure chamber of the plunger 12 through port 10 and interfere with the correct operation of the pump. Such flow of fuel also cools the various parts of the injector.

The rack 20, which controls the fuel delivery of the injector 6, is formed as a plunger slidably in a bore formed in housing 6. One end of rack 20 extends into a chamber 54 closed by a plug 56, to which chamber fuel is led from the inlet port 48 through a duct 58. A calibrated coil spring 60 is mounted between the opposite end of rack 20 and a cap 62 having a threaded connection with injector housing 6. A rod 64 of small diameter fixedly connected with rack 20 and coaxial therewith extends through a central opening of cap 62 and can be manually operated to temporarily modify the axial adjustment of rack 20.

The adjustment of rack 20 and in turn the fuel discharge of the injector are dependent on the value of the fuel pressure in the inlet port 48. An increase in fuel pressure causes a movement of rack 20 until the increased hydraulic load on the latter is balanced by a correspondingly increased resilient load of spring 60. The preferred arrangement is such that a displacement of rack 20 toward the left, as shown in Figure 3, deter-

mined by an increase in fuel pressure in inlet port 48 causes an increase of fuel delivery of the pump. The pressure of the fuel led to injector 6, and the fuel discharge thereof will therefore simultaneously increase or decrease according to a predetermined relationship. The maximum displacement of rack 20 toward the left is determined by cap 62; the maximum fuel discharge per stroke of the injector may therefore be set at a predetermined value by adjusting the thickness of gasket 66 interposed between cap 62 and housing 6. Furthermore, the spring 60 has a definite rate of deflection and its load is initially determined by adjusting the thickness of spacer 68 mounted at one end thereof so that with a given pressure at the inlet port 48 the pump 6 discharges a determined amount of fuel per plunger stroke. Pumps 6 are therefore interchangeable. Obviously, while in the example above disclosed the variable fuel pressure acts directly on rack 20, other pressure-responsive devices such as a piston, or flexible diaphragm or bellows may be provided for actuating the rack 20 or other injector fuel delivery control member. Control of the engine fuel supply may thus be obtained by governing the pressure of the fuel led to the various injectors 6 thereof. Figures 1 to 3 of the drawings show the injector 6 applied to an internal combustion engine, either of the compression-ignition or of the spark ignition type, having a cylinder block 70 and a cylinder head 72 clamped thereon with a gasket 74 interposed therebetween, and adapted to discharge fuel into the chamber 76 formed in the cylinder head 72. It is important that the injector be firmly attached to the engine and held in accurately determined position relative to the tappet or reciprocating mechanism 16. To that end the injector 6 is provided with a flange 80 the lower surface of which is normal to the axis of plunger 12 and is adapted to be clamped on the upper surface of the cylinder block 70 or other suitable machined surface thereof. In the upper wall of the cylinder block 70 an opening is provided, through which the lower part of the injector 6 extends into the tappet compartment.

A fuel line element 82 has at one end an expanded head 84 adapted to be clamped on the tapered wall of fuel inlet 48 of the injector by means of the retaining member 86, and at the opposite end an expanded head 88 against which one extension 90 of the fuel inlet manifold 92 is clamped by means of a threaded cap 94 thereby establishing a detachable fuel connection between inlet manifold 92 and inlet port 48 of injector 6. A fuel line element 96, similar to line element 82, forms a detachable fuel connection between the return outlet port 53 of the injector and the fuel return manifold 98. The retaining member 86 is supported at one end against the edge of a cavity 100 formed in the cylinder block 70, while at the other end it is clamped by means of a stud 102 secured to the engine head 72 and a nut 104, thus exerting on the head 84 of fuel line element 82 and on the similar head of fuel line element 96 loads sufficient to prevent any fuel leakage. The arrangement of the retaining member 86 and its attachment are such that the resultant of such loads transmitted to the injector 6 passes through or near the point of intersection of the axis of plunger 12 and nozzle 32 thereof, and forms a suitable angle, shown as 45 degrees in the drawings, with said axes, whereby said resultant is resolved into two component loads, one having

substantially the direction of plunger 12 and serving to clamp the injector on the engine block 70 against the thrust transmitted to the plunger by tappet 16; and the other having substantially the direction of the axis of nozzle part 32 of the injector and serving to clamp the latter and the gasket 106 thereof, or equivalent sealing means, against a suitable shoulder provided in the engine head 72.

Sufficient radial clearance is provided between the horizontally extending nozzle part 32 and cap 34 of the injector and the cavity of the cylinder head 72 in which said nozzle part and cap are mounted so as to avoid any binding when the injector is clamped into position, regardless of the changes in the thickness of gasket 14 interposed between the engine block 70 and the cylinder head 72. By this arrangement the danger of bending the housing of injector 6 and asymmetrically deforming the barrel 8 thereof is eliminated.

A camshaft 14 is supported in bearings carried by the engine block 70 and serves to actuate through push rods 110 the inlet and exhaust valves, not shown in the drawings, mounted in the head 72 of the engine. Any suitable tappet mechanism for actuating the plunger 12 of injector 6 from said camshaft may be provided. A convenient arrangement, shown in Figure 1, includes a cam follower of the mushroom type 112 reciprocably mounted in a guide 114 carried by the engine block 70 and provided with a cavity therein containing a retainer 116 urged against the spherical inner end of said cavity by the lower end of the coil spring 118, the upper end of which is held by cap 120 having a threaded connection with guide 114. The tappet rod 16 is provided at its lower end with an expanded head 122 held with small clearance between the end of said cavity and retainer 116, while at its upper end it carries a connecting member 47 having a permanent press fit in rod 16. Such connecting member 47 includes a head formed with a T-slot having a close fit with the head 44 formed at the lower end of pump plunger 12. A U-shaped retaining member 124 slidably mounted about the connecting member 47 is upwardly urged by a spring 126 to laterally close the T-shaped slot and eliminate the danger that the head 44 of plunger 12 may be accidentally disconnected from the connecting member 47. Said retaining member 124 is shown in its operating position in the drawings, but it may be displaced against the load of spring 126 to a position in which the tappet rod 16 may be disconnected from the pump plunger 12.

It is therefore clear that tappet rod 16 is centered at its lower and upper ends by the cam follower 112 and by the pump plunger 12 respectively, thus eliminating the necessity of providing guiding or supporting means therefor, and furthermore, it may be readily detached from the pump plunger 12. Thus, spring 118 holding the cam follower 112 in contact at all times with the cooperating cam carried by camshaft 14 also effects the return or suction stroke of pump plunger 12 of injector 6.

In the preferred embodiment of the invention the cam follower 112 and the tappet rod 16 are coaxial or substantially coaxial with the pump plunger 12 of the injector 6; hence slight changes in the position of injector 6, such as might be caused by changes in the thickness of nozzle gasket 106, do not cause any appreciable modification in the adjustment of pump

plunger 12 and therefore do not affect the timing of the injection. Furthermore, it is to be noted that, although the injection is effected through the walls of cylinder head 72 into the chamber 76, the distance of the injector 6 from the camshaft 14 is determined by the distance between the latter and the machined upper surface of the cylinder block 70 and is therefore independent of changes in the thickness of the cylinder head gasket 14. According to the preferred embodiment of the invention the distance between the camshaft 14 and the upper machined surface of the cylinder block 70 on which the injector 6 is clamped, the radii of the cam and the length of the tappet mechanism between cam and plunger 12 are all accurately kept within close predetermined tolerances: the result being that when the camshaft 14 is in a given angular adjustment, for example corresponding to the point of minimum lift of the tappet mechanism, the T-shaped slot of the connecting member 47 thereof and in turn the head 44 of the pump plunger 12 are within a close predetermined tolerance at a definite distance from the machined surface of flange 80. Preferably, the various elementary parts included in the tappet mechanism are machined within strict tolerances so that they may be individually replaced without affecting the total length thereof. Furthermore, in injector 6, when the head 44 of pump plunger 12 is at a definite distance from the lower surface of flange 80, that portion of plunger 12 which is adapted to cover and uncover the inlet port 10 of barrel 8, and thus controls the injection, is at correspondingly predetermined distance from said port 10, whereby all injectors 6 are interchangeable. Thus the injectors as well as the various parts of the tappet mechanism and the cylinder head gasket 14 may be replaced without requiring adjustment of the injection timing.

It may be shown that slight variations in the lengths of the various parts of the tappet mechanism and of the injector within reasonable manufacturing tolerances cause variations in the injection timing that usually are considerably smaller than one degree of crank shaft rotation. Injection timing is therefore far more accurate than with the conventional injection system including separate injection nozzle and fuel pump interconnected by a comparatively long high-pressure fuel line wherein pressure surges and fuel compressibility adversely affect the injection characteristic and the accuracy of the timing thereof.

The tappet mechanism compartment in the cylinder block 70 is enclosed by a cover 130, and the injector compartment in the cylinder head 72 is enclosed by another cover 132.

In order to inspect the operation of the injectors 6 in a multicylinder engine it is sufficient to remove the cover 130 and, while the engine is operating, push successively the rods 64 extending from the various injectors thereby temporarily shutting off the fuel delivery thereof. It may thus be promptly ascertained whether all the injectors 6 are operating correctly. In order to replace one of the injectors, the retaining member 124 of the tappet rod is moved downward against spring 126, and tappet rod 16 is disconnected from plunger 12. Then the cover 132 is removed, the threaded caps 94 are untightened to loosen the fuel line elements 82 and 96, and the nut 104 is unscrewed to permit removal of retaining member 86. Fuel line ele-

ments 82 and 96 are moved sidewise away from the injector 6 and the latter may be withdrawn with a translation at first horizontal in order to clear the nozzle tip 32, then vertical so that the lower expanded portion of the injector may pass through a suitable opening provided in the upper wall of cylinder block 70; whereupon the injector 6 may be removed from the cylinder head 72. The same operations in inverted order are necessary for assembling the injector on the engine.

The fuel manifolds 92 and 98 are attached to cylinder block 70 and need not be removed when the cylinder head 72 is disassembled. From the foregoing it will be appreciated that the injectors 6 may be readily and easily inspected and replaced, which is important not only in manufacturing but also in servicing in the field.

It has been stated in the foregoing that the fuel supply of the engine is controlled by adjusting the pressure of the fuel led to the injectors 6. To that end a fuel transfer pump 136 shown as a pump of the gear type mounted in a housing 138 attached to a wall of the cylinder block 70 includes a gear 140 driven from the engine cam-shaft 14 and meshing with an idler gear 144. The pump 136 draws fuel through supply lines 146 and 148 and discharges it under pressure into lines 150 and 152 and inlet manifold 92. In a multi-cylinder engine having several injectors 6, the latter are connected in parallel between fuel inlet manifold 92 and fuel return manifold 98. The fuel discharge of the transfer pump 136 is thus equally divided among the injectors, and the excess of said discharge, that is the amount of fuel which is not injected into the engine cylinders, serves to vent and cool the injectors, and is thereafter led through line 154 to a duct 156 communicating with a bore formed in valve body 158, in which bore is slidably and rotatably mounted a pressure regulating valve of the plunger type 160.

A speed governor includes a shaft 162 rotatable in a sleeve 164 and driven from camshaft 14 of the engine or other suitable shaft thereof. Shaft 162 coaxial with valve 160 carries flyballs 166 having inwardly extending arms which engage the lower end of valve 160, while the upper end of said valve carries the inner race of a ball-bearing 168. A governor spring 170 is mounted between the outer race of bearing 168 and seat 172 slidably mounted on a guide pin 174 carried by cover 176. A floating lever 180 is connected at one end with lever 182 carried by a shaft to which the throttle lever 184 is secured, at the other end with the plunger 186 slidably mounted in a bore formed in body 158, and at intermediate point with seat 172 of governor spring 170.

An annular groove 190 machined in the intermediate portion of valve 160 is in permanent communication with duct 156, while it communicates with groove 192 connected with line 148 through an annular opening whose area is dependent on the axial adjustment of valve 160. Plunger 186 is urged upwardly by the pressure of fuel in line 156 applied to its lower end, while the upper end thereof is loaded by a spring 194 wound about threaded screw 196 adjustably mounted in cap 198 and provided with a lock nut. The upper coil of spring 194 extends radially into a groove or opening provided in cap 198 so as to prevent angular rotation of the spring relative to the cap, the result being that the number of free or active coils of spring 194, and in turn its rate of deflection, may be varied by rotating the screw 196 relative to cap 198. Fur-

thermore cap 198 has a threaded connection with cover 176 and is also provided with a locking nut.

When the engine is inoperative the pressure in all fuel lines is the same as in the supply lines 146 and 148. The injectors 6 are adjusted for no delivery. The valve 160 is in its lower position and closes the communication between grooves 190 and 192. The plunger 186 is also in its lower position. Assuming the engine to be cranked, the fuel transfer pump 136 draws fuel from the supply line 146 and discharges it through lines 150 and 152 into the fuel inlet manifold 92. The fuel pressure rises rapidly and reaches its maximum value, which may be regulated by adjusting cap 198 relatively to cover 176, whereupon plunger 186 opens the by-pass 200 and prevents a further increase in pressure. Fuel is thus circulated through injectors 6, which helps remove all gas or vapor bubbles therefrom. Accordingly, the injectors 6 are adjusted for maximum fuel delivery and, actuated by tappet mechanism 16, inject fuel into the engine cylinders. As firing occurs in the latter and the engine speed increases and approaches the value corresponding to the setting of the throttle lever 184, valve 160 is lifted by the flyballs and establishes a fuel communication between grooves 190 and 192.

Since the capacity of the fuel transfer pump 136 is in excess of the total maximum discharge of injectors 6, when the engine is operating under the control of the governor, that is when the duct 200 is closed by plunger 186, the excess fuel is by-passed through the open area of the annular opening between grooves 190 and 192 controlled by valve 160. A downward displacement of the latter causes a reduction of area of said opening and therefore an increase in speed of the fuel flowing therethrough and a corresponding increase of pressure in the fuel lines. Conversely, an upward displacement of valve 160 causes an increase of said area, a reduction of speed of the fuel by-passed therethrough and a corresponding decrease of pressure in the fuel manifold. The adjustment of valve 160 relative to groove 192 is dependent on the simultaneous actions of the load of spring 170 and of the centrifugal force transmitted by flyballs 166. It is therefore dependent on the adjustment of the throttle lever 184, on the engine speed and on the adjustment of plunger 186.

Any governor of conventional character (with the exception of isochronous type) in order to be stable must regulate the speed of its engine in such a manner that the speed is lower for full load than for no load. If the difference between maximum and minimum speed divided by the average speed, or "speed droop" is high, the speed regulation is "soft" and the change from a given amount of engine fuel supply to another caused by a change of load on the engine is not abrupt but gradual. A smaller speed droop causes a more abrupt speed regulation because small speed variations involve large changes in the engine fuel supply. When the engine is operating under steady load the valve 160 is in stable equilibrium; if the engine load increases the engine speed decreases and the centrifugal force acting on flyballs 166 also decreases causing a downward movement of valve 160 and an increase of fuel pressure in the fuel manifold. The discharge of the injectors 6 increases and the engine resumes speed. The increased fuel pressure moves the plunger 186

upwardly against the load of spring 194 thus raising the left end of floating lever 180 and the seat 172 of spring 170. The load of the governor spring 170 being reduced, the equilibrium of the governor will be re-established at an engine speed corresponding to that value of the centrifugal force of flyballs 166 that balance the new load of spring 170. The engine speed under the heavier engine load will therefore be lower than the engine speed under lighter engine load.

Conversely, when a drop in engine load occurs the engine accelerates and the flyballs 166 lift the valve 160 causing a reduction of fuel pressure in the fuel manifolds. The fuel discharge of injectors 6 decreases causing a diminution of engine speed and determining a downward displacement of plunger 186 which in turn increases the load of governor spring 170. The decrease in engine load will therefore cause an increase of engine speed. The condition of stability of the governor, that is the ability to cause the engine speed to decrease when the engine load increases, is thus satisfied. The desired nominal engine speed is set by means of throttle lever 184, which may be adjusted by the operator or by automatic devices. Anti-clockwise rotation of lever 184 increases the load of spring 170 and in turn the engine speed. A stop may be provided to limit the anti-clockwise rotation of lever 184 thereby determining the maximum engine speed, while an adjustable resilient stop may limit the clockwise rotation of the lever to set the engine idling speed. Neither of the stops are shown in the drawings. Clockwise rotation of lever 184 beyond its position determined by the resilient stop causes valve 160 to substantially increase the area of passage between grooves 190 and 192 thereby stopping the engine.

Figure 4 shows a partially modified governor in which the speed droop is adjusted not by varying the number of active coils of spring 194 thereby changing the deflection rate thereof, but by controlling the rate of pressure change in compensating chamber 210 at the lower end of plunger 186, which chamber communicates with fuel lines 148 and 156 through orifices whose open areas may be adjusted by means of needle valves 212 and 214 respectively. If the orifice controlled by valve 214 is closed while the orifice controlled by valve 212 is open, the fuel pressure in chamber 210 is the same as in fuel supply line 146, the engine speed droop has its minimum value, substantially zero, and the governor is likely to be unstable. If needle valve 212 is closed and needle valve 214 is open the speed droop has its maximum designed value.

Obviously, when both needle valve 212 and 214 are open the fuel pressure in valve 210 has a value comprised between the pressures in lines 156 and 148. Assuming that the pressure in the latter is equal to the surrounding atmospheric pressure, the effective pressure p in the compensating chamber 210 is

$$p = \frac{p_1}{1 + \left(\frac{a_2}{a_1}\right)^2}$$

where p_1 is the effective pressure in line 156, and a_1 and a_2 are the open areas of the orifices controlled by needle valves 214 and 212 respectively. That is, the ratio between the fuel pressures in chamber 210 and in line 156 may be varied between one and zero by properly adjusting the needle valves 212 and 214. The speed droop varies substantially in proportion with said ratio.

Any determined value of speed droop within the designed limits of the governor corresponds to a definite ratio between the open areas controlled by needle valves 212 and 214. Yet the open area of one or the other of said orifices may be arbitrarily chosen so as to obtain a suitable dampening effect, or "dash pot" action, on plunger 186.

The only friction that the governor has to overcome is that opposing the axial displacements of plunger 186 and valve 160. Since the latter rotates together with flyballs 166 the friction opposing its axial movement has a very low value. Friction opposing the axial displacement of racks 20 of the injectors 6 does not influence the operation of the governor. If one of the pump plungers 12 should stick in its barrel and remain stationary at the end of its discharge stroke with the load of spring 118 insufficient to bring it back, the pump would stop delivering fuel to its cylinder but it would not interfere with the control of the remaining injectors, while with the conventional mechanical linkage interconnecting all the racks 20 the damaged injector might prevent the regulation of the other injectors thereby putting the engine out of control.

The effect of the frictional resistance opposing the axial movement of the racks 20 is reduced or eliminated by the pressure surges caused by the rapid opening and closing of ports 10 and 30 transmitted to the chambers 54 through conduit 58. Owing to said surges the hydraulic load applied to the racks 20 has a pulsating character. The range of said high-frequency pulsation of the load applied to the racks may be reduced, if it should appear desirable, by reducing the section of conduit 58 or otherwise increasing the resistance to the flow of fuel therethrough.

Non-adjustable orifices may obviously be substituted for one or both of the needle valves 212 and 214. The fuel manifolds 92 and 98, and the conduits connecting the latter with duct 156 of the governor are of such large sections that under all operating conditions the fuel pressure in the injectors and in duct 156 is substantially the same. Between the discharge port of the transfer pump 136 and the fuel line 150 a fuel strainer or filter, not shown in the drawings, may be inserted.

In Figure 5 automatic safety devices are shown for shutting off the engine fuel supply. The engine-driven fuel transfer pump 136 including gears 140 and 144, draws fuel at substantially constant pressure from supply line 146 and discharges a weight of fuel proportional to the engine speed through a line 218 and an orifice adjustable by needle valve 220 into line 222 leading to the inlet manifold 92, thus determining on opposite sides of said orifice a difference of pressure that is proportional to the square of the engine speed. A plunger 224 slidably mounted in a bore formed in pump housing 226 is provided with an annular groove 228 in constant communication with line 222 and, through duct 230 drilled in plunger 224, with a chamber 232 formed at the lower end of the plunger and closed by a threaded cap. The upper and lower ends of plunger 224 are submitted to the pressure of the fuel respectively ahead and beyond the orifice controlled by needle valve 220 whereby a downwardly directed hydraulic load proportional to the square of the engine speed is applied to said plunger against the load of the spring mounted in chamber 232. When a predetermined engine speed is reached plunger 224 moves downward establishing by

means of its groove 228 a communication between line 222 and a groove 234 connected with low pressure fuel supply line 148, thereby opening a by-pass between the discharge and inlet ports of transfer pump 136, thus causing the pressure in the fuel manifold to drop and stopping the fuel discharge of injectors 6. The engine speed at which the plunger 224 by-passes the transfer pump 136 may be adjusted by means of needle valve 220, or by varying the thickness of gasket 236 and the load of the spring mounted in chamber 232. Said speed is preferably substantially higher than the maximum speed at which the main governor may be set, and plunger 224 is therefore an auxiliary independent over-speed shut-off device intended to operate in case of failure of the main governor. It may, however, be used as a maximum-speed governor, for example, in connection with an internal combustion engine of automotive type.

Other simple, compact, and inexpensive safety devices may be provided for shutting off the engine fuel supply in response to variations beyond predetermined limits of temperatures, or pressures connected with the operation of the engine. In their preferred embodiment they include means for controlling a by-pass adapted to connect the fuel pressure lines communicating with the fuel manifolds 92 and 98 with a low pressure supply line 148.

An example of temperature-responsive shut-off device is shown in Figure 5, in which a bulb 240 containing a liquid having a boiling point of a value such that at a predetermined temperature the fluid will produce a substantial increase of pressure in chamber 242 suitably connected with bulb 240 and closed by a membrane or bellows 244 adapted to actuate an axially slideable plunger 246 against the load of spring 248. Upward displacement of plunger 246 causes the groove 250 connected with line 222 to communicate with chamber 252 connected with low-pressure supply line 148, thereby determining a drop of pressure in the fuel manifolds and stopping the engine fuel supply. By means of a suitable duct drilled in plunger 246 the fuel pressure at the upper end thereof is kept at the same value as in chamber 252. Bulb 240 or equivalent temperature-responsive devices adapted to actuate plunger 246 may be mounted and arranged in suitable places so as to actuate plunger 246 and stop the engine when the exhaust temperature, or the lubricating oil temperature, or the cooling water temperature, or the temperature of any suitable part of the engine reaches a predetermined value.

An example of pressure-responsive device is also shown in Figure 5, in which a fluid is led through pipe 260 to a chamber 262 closed by a membrane or bellows 264 adapted to actuate an axially slideable plunger 266 against the load of a spring. An annular groove 268 provided in plunger 266 is connected by means of suitable ducts with a chamber at the upper end of plunger 266 and chamber 270 communicating with the low pressure line 148. When the pressure of the fluid contained in line 260 and chamber 262 drops below a predetermined value plunger 266 moves downwardly thereby establishing a communication between groove 272 and chamber 270 through annular groove 268 and the axial duct drilled in the plunger, thus by-passing the transfer pump 136. An increase in pressure in chamber 262 beyond a predetermined limit also causes a communication to be established be-

tween groove 272 and chamber 270, as it has already been described in detail in connection with plunger 246. Line 260 may be connected with the lubricating oil line of the engine, the result being that when the pressure in said line is below a given value no fuel is injected into engine cylinders. The fuel injection is also stopped when the pressure in said line increases beyond a determined value, as may happen when the oil filter is clogged.

In Figures 6 and 7 there is shown an injector 280 similar to injector 6 but provided with different attaching means and fuel connections. Injector 280 has a flange 282 the lower surface of which is machined and adapted to be clamped on the upper machined surface of cylinder block 284 (or other suitable surface thereof), in which is provided an opening through which the lower part of injector 280 may be introduced in the tappet compartment 286. The injector fuel inlet 290 and fuel return outlet 292 are formed in said flange, communicating with fuel ducts 294 and 296 drilled in the engine block 284 and connected with fuel inlet conduit 298 and fuel return conduit 300 respectively, these conduits having the same function as the fuel manifolds 92 and 98 of Figure 1. Small fuel filters or strainers 302 may be provided in the fuel inlet and fuel outlet of injector 280, together with sealing means 304 consisting preferably of an annular member made of plastic or resilient material for preventing fuel leakage between flange 282 and cylinder block 284. A cap screw 306 having a threaded connection with the cylinder head 308 serves to clamp injector 280 in position, the load transmitted therebetween indicated by arrow 310, being substantially in line with the point of intersection of the axes of plunger 12 and nozzle 32, and having preferably the approximate direction of the bisectrix of the angle formed by said axes so as to be resolved into component loads indicated by arrows 312 and 314 of substantially equal magnitudes. Said components coincide approximately with said axes, thus eliminating the danger of bending the pump and nozzle parts of the injector, clamping the gasket 106 between nozzle tip 32 and cylinder head 308 and clamping flange 282 of injector 280 on cylinder block 284 thereby holding fuel seals 304 of the inlet and outlet of the injector 280 under compression. Centering shoulders 320 and 322 cooperating with cap screw 306 are provided in injector 280 for centering the latter and preventing sidewise displacement thereof.

It will be appreciated that injector 280 may be readily and easily removed from the engine and replaced thereon, without requiring any timing adjustment of the injection. In order to remove the injector, cover 230 is disassembled and tappet rod 16 is disconnected from plunger 12; then cover 232 is removed and cap screw 306 is unscrewed, whereupon injector 280 may be withdrawn from the cylinder head 308. The same operations in inverted order are necessary for assembling the injector on the engine and reestablishing the fuel connections therebetween.

In the foregoing examples of preferred embodiments of the invention hydraulically controlled injectors have been disclosed, whose fuel delivery is regulated by adjusting the pressure of the fuel supplied thereto. It is to be clearly understood, however, that according to the invention any appropriate fluid other than the engine fuel may be employed as hydraulic medium for the pressure-actuation of the injector rack 20, or other

equivalent fuel delivery control member of the injector. Similar hydraulically controlled fuel injector arrangements have been disclosed in some among my previously identified copending patent applications, wherein lubricating oil under variable pressure may be used for actuating the fuel delivery control member thereof. Furthermore, a continuous flow of lubricating oil or other appropriate liquid coolant may be used to cool the injector. In any case the injector is to be connected with one or more pipes or conduits for leading thereto, and possibly returning therefrom, an appropriate fluid such as the engine fuel, lubricating oil or other suitable liquid coolant, etc., and accordingly one of the objects of the invention resides in the provision of common means for readily and simultaneously clamping the injector on the engine and connecting it in flow communication with one or more pipes or conduits containing such fuel or other fluid. It will be readily understood that the injector 6 of Figs. 1 to 3 may be so modified, if desired, that one of the pipes 82 connected therewith will supply low pressure fuel to the inlet port 10 of the pump cylinder 8 thereof, while the other pipe may be used to lead another fluid, for example lubricating oil under variable pressure, to the chamber 54 at one end of rack 20 for the hydraulic actuation of the latter. In such a case the hydraulic governor will be used to control the pressure of lubricating oil in the latter pipe.

It will be further understood that in the case of the injector 280 of Figs. 6 and 7, more than two ducts opening in the injector flange and cooperating with an equal number of conduits opening in the corresponding flange-supporting engine surface may be provided. Thus in addition to the low pressure fuel lines connected with the inlet port 10 of the pump cylinder 8 for delivering fuel thereto, and venting the injector to prevent vapor-lock, two more conduits connected with chamber 54 and with appropriate cooling passages in the injector, may be provided for establishing a continuous flow of a suitable fluid such as lubricating oil under variable pressure to cool the injector, and exert an operative variable pressure-load on the control rack 20 thereof. In this arrangement said lubricating oil is employed as hydraulic medium in the governor of Fig. 1, and in the control devices of Fig. 5 for the control of the engine fuel supply. No matter what the number of conduits opening in the injector attachment flange and in the corresponding supporting engine surface, and no matter what the fluid or fluids in said conduits may be, a common fastening element such as bolt 306 may be used. The modifications which may be required in the injectors in order to use a fluid other than the engine fuel to cool the pump 8, and hydraulically control the rack 20, are evident and obvious to those skilled in the art.

It is further to be understood that according to the invention the injector need not be of the type including a pump and a nozzle body mounted transversely with respect to one another, but that any suitable type of injector adapted to be connected in flow communication with one or more fluid conduits, may be used in combination with common means for simultaneously clamping the injector on the engine, and tightly connecting said injector with said conduit or conduits.

These embodiments of the invention have been shown merely for purpose of illustration and not as a limitation of the scope of the invention. It

is therefore to be expressly understood that the invention is not limited to the specific embodiments shown, but may be used in various other ways, and various modifications may be made to suit different requirements, and that other changes, substitutions, additions and omissions may be made in the construction, arrangement and manner of operation of the parts within the limits or scope of the invention as defined in the following claims. Where the claims are directed to less than all of the elements of the complete system disclosed, they are intended to cover possible uses of the recited elements in installations which may lack the non-recited elements.

15 Certain features disclosed herein are claimed in my copending patent applications referred to above.

What I claim is:

1. In combination with an internal combustion engine including a cylinder block having a machined surface, a detachable fuel injector including an injection nozzle and a plunger pump having their axes substantially at right angles; a gasket at the end of said nozzle; flange means 20 for said injector whereby the latter may be clamped on said surface with the axis of said pump perpendicular thereto; a fuel inlet and a fuel return outlet in said injector; fuel lines having their ends adapted to be detachably connected with said inlet and said outlet; and attaching means for clamping said ends of said lines on said inlet and said return outlet thereby transmitting to said injector a load which is resolved into two component loads substantially in 25 line with said two axes for clamping said flange means against said machined surface, and for applying sealing pressure to said gasket.

2. In combination with an internal combustion engine having a machined surface and a thrust 30 surface, a fuel injector having a flange for attachment to said machined surface and including a plunger pump perpendicular to said flange and a nozzle body extending parallel to said flange and adapted to be held against said thrust surface; and attaching means for simultaneously 35 clamping said flange against said machined surface and thrusting said nozzle body against said thrust surface.

3. In combination with an internal combustion 40 engine having a plane surface and an annular seat for a nozzle body, a fuel injector having a face adapted for attachment to said plane surface, and a nozzle body substantially parallel to said face; and means for simultaneously clamping 45 said face on said plane surface and thrusting said nozzle body against said seat.

4. In combination with an internal combustion engine having a seat for an injection nozzle body, a plane surface and a fuel feed duct opening in 50 said surface, a fuel injector unit including flange means for attachment to said surface, a plunger pump perpendicular to said flange means, conduit means opening in said flange means for leading fuel from said duct to said pump, and a nozzle body extending transversely with respect with 55 said pump; and common means for holding said unit with said flange means and nozzle body clamped on said surface and seat respectively.

5. In combination with an internal combustion engine having a seat for a nozzle body, a plane surface, and fuel feed and excess fuel return ducts opening in said surface, a fuel injector unit including flange means for attachment to 60 said surface, a plunger pump perpendicular to said flange means, conduit means opening in said

flange means for establishing a fuel flow communication between said pump and said feed and return ducts to vent and cool said injector, and a nozzle body extending transversely with respect to said plunger, and common means for clamping said flange means and nozzle body of said unit against said surface and seat respectively.

6. In combination with an engine having a machined surface and a thrust seat, an injector including a finished face, a fuel plunger pump perpendicular to said face, a delivery valve body extending transversely with respect to said pump and fuel inlet means, fuel conduit means adapted for connection with said inlet means, and common means for attaching said conduit means to said inlet means, clamping said face on said surface and thrusting said valve body on said seat.

7. In combination with an engine, a fuel injector including a plunger pump, a nozzle valve body extending transversely with respect with said pump, and a flange perpendicular to said pump for attachment to said engine, conduit means adapted for detachable connection with said injector to circulate a liquid coolant therein, and common means for connecting said conduit means with said injector and applying to the latter clamping loads in the directions of said pump and valve body.

8. In combination with an engine having a camshaft, inlet and exhaust valves actuated from said camshaft, a finished surface at definite distance from said camshaft, and a nozzle body seat, a fuel injector including a flange for attachment to said surface, a pump having a reciprocable plunger actuated from said camshaft and perpendicular to said flange, and a nozzle body extending transversely with respect to said plunger and a single threaded member for holding said injector with said flange clamped on said surface, and said nozzle body thrust against said seat.

9. In combination with an engine having a cylinder block provided with a machined surface, a cam at definite distance from said surface, and a cylinder head mounted on said block with a gasket interposed between block and head, a passage provided with a seat in said head, a fuel injector having a face for attachment to said surface, a plunger pump perpendicular to said face and actuatable from said cam, and a nozzle body extending transversely with respect to said pump, and common means for holding said injector with said face clamped on said surface and said nozzle body thrust against said seat, with sufficient radial clearance between said passage and nozzle body to compensate for variations in the thickness of said gasket.

10. In combination with an internal combustion engine, a fuel pump and injection nozzle unit therefor, a seat in said engine for said unit, fuel conduit means adapted for detachable connection with said unit, and common attachment means for simultaneously connecting said conduit means with said unit and clamping said unit on said seat.

11. In combination with an internal combustion engine, a fuel injector unit therefor including a plunger pump and a nozzle body, a seat in said engine for said nozzle body, fuel pipes adapted for detachable connection with said unit to lead low pressure fuel to said pump and return the excess fuel therefrom, and common attachment means for connecting said pipes with said unit and thrusting said nozzle body on said seat.

12. In combination with an internal combustion engine, a fuel injector therefor, a seat in said engine for said injector, duct means in said injector, conduit means adapted for detachable connection with said duct means for the circulation of a liquid coolant in said injector, and common attachment means for simultaneously connecting said conduit means with said duct means and clamping said injector on said seat.

13. An engine fuel injector having a flange for attachment to the engine, fluid pressure responsive means in said injector for controlling the fuel delivery thereof, a fluid conduit adapted for detachable connection with said injector for leading thereto fluid under variable pressure to actuate said pressure responsive means, and common means for simultaneously clamping said flange on said engine and connecting said conduit with said injector.

14. An engine fuel injection pump having a fuel discharge passage, a thrust surface surrounding said passage and a plane surface substantially parallel to said passage for attachment of said pump to the engine, and a threaded member connected with said pump for exerting simultaneous fastening loads in the directions of said thrust and plane surfaces.

15. In combination with an engine having a plane surface and a seat, a fuel injection pump therefor including a fuel discharge passage, a thrust surface surrounding said passage, a flange substantially parallel to said passage, and fuel ducts opening in said flange, fuel conduits in said engine opening in said plane surface and adapted for connection with said ducts to lead fuel to said pump and return the excess fuel therefrom, sealing means deformable upon application of said flange on said plane surface to prevent fuel leakage therebetween, and a threaded member for simultaneously clamping said flange and thrust surface on said plane surface and seat respectively.

16. In combination with an internal combustion engine, a fuel injector unit therefor including a pump, a nozzle body, and fluid pressure responsive means for controlling the fuel delivery of said pump, a seat in said engine for said nozzle body, a pipe adapted for detachable connection with said unit for leading thereto fluid under variable pressure to actuate said pressure responsive means, and a retaining member for simultaneously connecting said pipe with said unit and clamping said nozzle body on said seat.

FERDINANDO C. REGGIO.
